UNITED STATES PATENT OFFICE.

EDWARD A. LANGENBACH, OF CANTON, OHIO.

DESIGN FOR A MOLDING-PLATE.

SPECIFICATION forming part of Design No. 26,236, dated November 3, 1896.

Application filed September 23, 1896. Serial No. 606,781. Term of patent 7 years.

To all whom it may concern:

Be it known that I, EDWARD A. LANGENBACH, a citizen of the United States, and a resident of Canton, county of Stark, State of Ohio, have invented and produced a new and useful Design for Molding-Plates, of which the following is a full, clear, and exact description, reference being had to the accompanying drawings, making part of this specification.

The invention relates to a new design for a metallic border; and it consists of a plate of the configuration and ornamentation shown in the accompanying drawings, in which—

Figure 1 is a plan view of the border made according to my design, and Fig. 2 is a sectional view of the same.

The leading feature of my design is a plate A, having the flat body portion 1, the outwardly-bulged portion 2, composed of the two curved lines 3 and 4 and the straight line 5, connected with the lines 3 and 4 by ribs 6, while the rib 7 connects the line 3 with the body 1. The lower marginal edge is formed

with parallel ribs 8. The body portion of the plate is divided off into panels 9 by pointed figures 10, the upper ends of which are bifurcated and formed into ornamental scrolls 11, from which appear to depend leaves 12, while ornamental scrolls 13 are arranged between the lower ends of the pointed figures and in connection with the pointed figures. Their bifurcated ends and the leaves form the panels, the fields of which are ornamented by curved lines or flourishes 14. The curved portions 3 and 4 are provided with reversely-arranged ornamented arches 15, inclosing pointed figures 16, while the intervening surface is perfectly plain.

What I claim is—

The design for a metallic border as herein shown and described.

In testimony whereof I have hereunto set my hand this 30th day of July, A. D. 1896.

EDWARD A. LANGENBACH.

Witnesses:

W. K. MILLER,
BURT A. MILLER.
